UNITED STATES PATENT OFFICE.

LEON T. SHANNON, OF RENO, NEVADA, ASSIGNOR OF TWO-FIFTHS TO ARTHUR P. LEWIS AND ONE-FIFTH TO JAMES B. JONES, OF RENO, NEVADA.

ROTARY ENGINE.

1,157,811.

Specification of Letters Patent.

Patented Oct. 26, 1915.

Application filed August 19, 1914, Serial No. 857,590. Renewed September 1, 1915. Serial No. 48,576.

To all whom it may concern:

Be it known that I, LEON T. SHANNON, citizen of the United States, residing at Reno, in the county of Washoe and State 5 of Nevada, have invented certain new and useful Improvements in Rotary Engines, of which the following is a specification, reference being had to the accompanying drawings.

10 This invention relates to improvements in internal combustion engines and more particularly to engines of the rotary type, the primary object of my invention residing in the provision of a very simple and compact 15 arrangement of the several parts whereby loss of energy incident to undue friction is eliminated and a very powerful operating force is obtained from a minimum consumption of fuel.

20 The invention has for a more particular object to provide in an engine of this character, a rotor provided with a plurality of self-contained propelling pistons.

In its more specific aspect the invention 25 includes a rotor fixed upon the power shaft and mounted within a suitable case, the opposite side walls of the case being provided with cam-ways, a plurality of radially extending slots formed in the rotor and opening 30 upon the periphery thereof, and pistons to reciprocate in the respective slots provided with trunnions movable in said cam-ways whereby the pistons are alternately moved inwardly and outwardly in the operation of the engine.

35 With the above and other objects in view, the invention consists in novel features of construction, combination and arrangement of parts as will be hereinafter referred to 40 and more particularly pointed out in the specification and claims.

45 For a full understanding of the invention, reference is to be had to the following description and accompanying drawings, in which:

Figure 1 is a vertical section through the engine case, one of the reciprocating pistons in the rotor being illustrated in position to receive the impact of the exploded 50 gas. Fig. 2 is a horizontal section taken on the line 2-2 of Fig. 1. Fig. 3 is an edge view of the rotor removed from the engine case. Fig. 4 is a detail diametrical section illustrating the manner of lubricating the 55 reciprocating pistons. Fig. 5 is a fragmen-

tary inner face view of one side of the motor case, the same being shown partially in section. Fig. 6 is an enlarged detailed section through one of the pistons, and Fig. 7 is a section taken on the line 7-7 of Fig. 6. 60

Referring in detail to the drawings 5 designates the base of the engine case with which the annular body wall indicated at 6 is preferably integrally formed. The side plates 7 of the engine case are removably 65 secured to said annular body wall by means of a plurality of screws or bolts indicated at 8. The body wall 6 is formed with a water compartment or chamber shown at 9, having an outlet port 10 on one side of 70 the case and an inlet port 11 at the opposite side thereof. These ports are interiorly threaded and adapted to receive suitable pipes as will be readily understood. In the top of the case wall 6 at the center thereof 75 a spark plug 12 of any approved form is arranged. The side plates 7 of the engine case are each formed with the hollow tapering bracing ribs 13. These ribs are integrally connected by the outer walls of the 80 side plates and the side flanges of said ribs are each formed with a series of openings 14 which afford means of connection between the several divisions or water compartments 15 of the hollow side plates of 85 the engine case. One of the hollow ribs 15 at its outer end is connected through the medium of an opening 16 with the annular water chamber 9 in the body of the engine case, and through these openings and the 90 hollow ribs 13 the water is conducted from one side of the case to the other. In this manner it is seen that there is a constant circulation of the water through the chambers in the annular wall 6 and the side 95 plates 7 whereby the engine case is properly cooled.

Each of the side plates 7 is centrally provided with an opening in which a bronze bearing bushing 17 is suitably secured. The 100 plates 7 are each provided between their inner and outer walls with an annular wall 18 which constitutes the inner end walls of the ribs 13 and the water compartments 15. Thus a circular chamber 19 is produced between the periphery of the bearing bushing 17 and the water chambers 15. The casing plates 7 are formed with passages 20 which communicate with the chamber 19 and extend downwardly therefrom through the 105 110

base 5 and open through said base to the atmosphere. These circular chambers 19 will be hereinafter referred to as "breathing" chambers, and the applicability of this term will be better understood as the construction and manner of operation of the engine is unfolded.

21 designates the power shaft which is mounted in the bearing bushings 17. Upon this shaft the disk or rotor 22 is keyed or otherwise suitably fixed. As is clearly shown in Fig. 1 of the drawings this rotor is provided with a plurality of radially extending slots or guide-ways 23. These slots terminate at their inner ends in spaced relation to the power shaft upon which the rotor is mounted, but open at their outer ends upon the periphery of the rotor. In each of the slots 23 a piston 24, to be hereinafter described in detail, is mounted for longitudinal sliding movement.

Upon the inner face of each of the side plates 7 of the rotor case a disk 25 is secured in any suitable manner. A cam-way or track indicated at 26 is cut through this disk, so that the central portion 27 thereof is completely separated from the outer or body portion of the disk. It will be noted that the cam-way 26 is symmetrical in contour on opposite sides of the shaft 21 and, in the direction of its length, extends to the same distance above and below said power shaft. This cam-way includes the opposed outwardly curved portions 26^a above and 26^b below the power shaft which are connected by the inwardly curved portions 26^c at the center of the disk. The face of the disk 25 is provided with an annular groove 28, concentrically related to the power shaft and located between the inwardly curved central portions 26^b of the cam-way. This groove is connected at spaced intervals by means of openings 29 in the disk and coinciding openings 30 in the inner wall of the case plate 7, with the breathing chamber 19. The groove 28 is of such diameter that the inner ends of the several piston slots 23 lap over the same and communicate therewith.

The slots 23 open upon each face of the rotor 22 and it will therefore be understood that the pistons 24 are rectangular in form. Each of said pistons includes a hollow body portion provided upon one end with a solid extension 31 in each surface of which a plurality of grooves 32 are formed. In these grooves suitable packing strips 33 are arranged and leaf springs 34 are disposed within said grooves behind the packing strips and act to force said strips outwardly from the grooves into frictional engagement with the opposed walls of the slots 23 and the faces of the disks 25. A rod 35 extends through the hollow body of the piston 24 and projects beyond the opposite ends thereof, as clearly shown in Fig. 6 of the draw-

ings. Upon these projecting ends of the rod or pin 35 bronze sleeves 36 are secured. These sleeves are disposed within the cam-ways 26 of the respective disks 25 and freely move or travel in said grooves in the rotation of the rotor 22.

The base 5 of the engine case is provided upon one side with an intake port 37 and upon its opposite side with an exhaust port 38. The inner surface of the annular body wall 6 of the case is provided with relatively narrow circumferentially extending grooves or channels 39 which connect at their lower ends with the intake and exhaust ports respectively. These channels terminate at their upper ends substantially in line with the axis of the shaft 21. It will be understood that a suitable gaseous mixture is supplied to the engine case through the intake port 37 thereof.

In the periphery of the rotor 22 and upon opposite sides of the outer open end of each slot 23 spring pressed packing strips 40 are arranged in grooves or channels for contact with the inner surface of the annular body wall 6 of the engine case whereby the escape of the gas held within the slot 23 or between the periphery of the rotor of the case wall is effectually prevented.

As thus far described the operation of the engine will be understood as follows: The uppermost piston 24, referring to Fig. 1 of the drawings, is at the limit of its movement in one direction and has compressed a charge of gas in the outer end of the slot 23 and the opening or chamber in the case wall 6 in which the spark plug 12 is arranged. The spark being now created by suitable timing mechanism this compressed gaseous charge is exploded and the piston driven inwardly. It is to be particularly observed that the bearing sleeves 36 of the piston are disposed slightly to the left of the point or apex of the cam-way. Thus as the piston is driven inwardly the bearing sleeves are forced to the right in the cam-ways, the pressure of the piston against the wall of the slot 23 driving or rotating the rotor 22 in the corresponding direction. As the bearing sleeves carried by the piston travel outwardly in the upper right hand portion of the cam-way, said piston moves inwardly until said sleeves are disposed within the inwardly curved central portions 26^b of the cam-ways at which point the piston is at the extreme limit of its inward movement. Slightly before reaching this position, a second piston carried by the rotor has arrived opposite to the spark plug 12, so that a second charge of gas is exploded and the rotation of the rotor thus continued without interruption or diminution. After the piston passes below the inwardly curved portions 26^b of the cam-ways it starts upon its outward movement in the slot 23 and the outer open end

on said slot is also in connection with the upper end of the exhaust passage or channel 39, so that the burned gas is driven outwardly by the piston and expelled from the slot 23, said gas traveling downwardly in the channel 39 and into the port 38 from which it is exhausted to the atmosphere. When the piston 24 is at the lower side of the rotor and in the extreme outer end of the slot 23, the sleeves 36 on the rod 35 are located at the lowest point of the cam-ways 26. Upon continued movement of the rotor, the piston 24 is again drawn inwardly as it moves past the intake port 37, so that a new charge of gas is drawn into the slot 23. This intake continues during the upward travel of the piston on the left hand side of the engine shaft until the outer open end of the slot 23 is disposed above the channel 39 in the wall 6. The bearing sleeves 36 now travel in the outwardly curved upper left hand portions of the cam-ways 26, so that the piston is forced outwardly and the gas compressed. This compression continues until the piston is disposed in its uppermost position at which point the explosion takes place. Thus an added rotary impulse is imparted to the rotor 22 in each 60° of its revolution. Of course it will be obvious that the number of explosions will correspond to the number of pistons which may be provided in the rotor, and the power to be derived from the engine increased or decreased accordingly. As each of the pistons is moved inwardly in the respective slots 23, in the manner above explained, the air back of said piston is expelled into the annular grooves 28 in the faces of the disks 25 and through the openings 29 and 30 into the breathing chambers 19 in the side plates 7 of the engine case. This air finds its exit through the passages 20. It is thus apparent that the occurrence of an air cushion behind the piston which would retard its movement and operate as a counteracting force to the rotation of the rotor is obviated.

I have also provided means for thoroughly lubricating each of the pistons 24 and the walls of the slot in which it travels. To this end the power shaft 21 is formed with a central longitudinal bore 41 to which lubricating oil is supplied from any suitable source. The inner end of this bore at the center of the rotor 22 is outwardly extended as at 42 and opens into a peripheral groove 43 formed in the shaft. The rotor 22 is provided with a series of radially extending passages 44 communicating at their inner ends with said groove and at their outer ends with the respective slots 23. In this manner it will be seen that a suitable lubricating oil may be constantly supplied to the several pistons during the operation of the engine.

From the foregoing description taken in connection with the accompanying drawings, it is believed that the construction, manner of operation and several advantages of my improved rotary engine will be clearly and fully understood. By providing the rotor 70 with the self-contained radially movable pistons, I am enabled to obtain a very compact arrangement of the several elements whereby loss of energy is reduced to a minimum and a maximum driving power obtained with a minimum consumption of fuel. Access may be easily and quickly had to the interior of the case for the purpose of renewing the packing rings upon the pistons by simply removing one of the face plates 7 80 of the engine case.

I have above described the particular construction of the pistons 24, which construction is preferable, as it is essential that the pistons shall be light in weight and at the same time of the requisite strength to satisfactorily sustain the pressures to which they will be subjected. It is, however, to be distinctly understood that in the practical development of the invention it may be found 90 advisable to alter the construction of these pistons in various particulars. The several other structural features above described are also to be considered as simply illustrative of one desirable embodiment of the invention, and I therefore reserve the privilege of resorting to all such legitimate changes as may be fairly embodied within the spirit and scope of the invention as claimed.

What I claim is:

1. In a rotary engine, an engine case, a rotor mounted within said case and provided with a plurality of slots, a piston mounted to reciprocate in each of the slots, each of the side walls of the engine being provided with a passage opening to the atmosphere, each of the case walls also having a plurality of openings therein affording communication between the inner ends of the respective slots in the rotor and said passage, whereby the air is exhausted from the inner ends of said slots in the inward movement of the respective pistons.
2. In a rotary engine, an engine case, a rotor mounted within said case and provided with a plurality of slots, a piston mounted to reciprocate in each of the slots, each of the side walls of the case being provided with an annular chamber and a passage leading from said chamber to the atmosphere, said case wall also having openings therein affording communication between the chamber and the respective slots in the rotor whereby the air is exhausted from the inner ends of said slots in the inward movement of the respective pistons.
3. In a rotary engine, a case, a rotor mounted within said case and provided with a plurality of radial slots opening upon the periphery thereof, pistons arranged in the

respective slots, said case being provided with intake and exhaust ports, ignition means mounted in the case, a disk secured to each of the side walls of the case and provided with a cam-way, a pin carried by each of the pistons having its ends disposed in said cam-ways whereby the respective pistons are alternately moved inwardly and outwardly in each revolution of the rotor to draw a charge into the respective slots, then compress the same and subsequently expel the burned gases through the exhaust port, and means for exhausting the air from the inner ends of the slots in the inward movement of the pistons.

4. In a rotary engine, a case, a rotor mounted within said case and provided with a plurality of radial slots opening upon the periphery thereof, pistons arranged in the respective slots, said case being provided with intake and exhaust ports, ignition means mounted in the case, a disk secured to each of the side walls of the case and provided with a cam-way, a pin carried by each of the pistons having its ends disposed in said cam-ways whereby the respective pistons are alternately moved inwardly and outwardly in each revolution of the rotor to draw a charge into the respective slots, then compress the same and subsequently expel the burned gases through the exhaust port, each of said disks being provided with an annular groove in communication with the inner ends of the slots in the rotor and a plurality of openings communicating with said groove, the side walls of the rotor case each having an air receiving chamber and passages connecting said chamber with the openings in the disk whereby the air from the respective slots in the rotor is expelled into said chambers during the inward movement of the piston.

5. In a rotary engine, a case, a rotor mounted within said case and provided with a plurality of radial slots opening upon the periphery thereof, pistons arranged in the respective slots, said case being provided with intake and exhaust ports, ignition means mounted in the case, a disk secured to each of the side walls of the case and provided with a cam-way, a pin carried by each of the pistons having its ends disposed in said cam-ways whereby the respective pistons are alternately moved inwardly and outwardly in each revolution of the rotor to draw a charge into the respective slots, then compress the same and subsequently expel the burned gases through the exhaust port, and means for exhausting the air from the inner ends of the slots in the inward movement of the pistons.

6. In a rotary engine, a case, a rotor mounted within said case and provided with a plurality of radial slots opening upon the periphery thereof, pistons arranged in the respective slots, said case being provided with intake and exhaust ports, ignition means mounted in the case, a disk secured to each of the side walls of the case and provided with a cam-way, a pin carried by each of the pistons having its ends disposed in said cam-ways whereby the respective pistons are alternately moved inwardly and outwardly in each revolution of the rotor to draw a charge into the respective slots, then compress the same and subsequently expel the burned gases through the exhaust port, each of said disks being provided with an annular groove in communication with the inner ends of the slots in the rotor and a plurality of openings communicating with said groove, the side walls of the rotor case each having an air receiving chamber and passages connecting said chamber with the openings in the disk whereby the air from the respective slots in the rotor is expelled into said chambers during the inward movement of the piston.

In testimony whereof I hereunto affix my signature in the presence of two witnesses.

LEON T. SHANNON.
